UNITED STATES PATENT OFFICE.

UTLEY WEDGE, OF ARDMORE, PENNSYLVANIA, ASSIGNOR TO THE FURNACE PATENT COMPANY, OF PHILADELPHIA, PENNSYLVANIA, A CORPORATION OF PENNSYLVANIA.

SECURING RABBLE-ARMS OF ROASTING-FURNACES.

1,037,091.

Specification of Letters Patent. Patented Aug. 27, 1912.

Application filed March 8, 1910. Serial No. 548,023.

To all whom it may concern:

Be it known that I, UTLEY WEDGE, a citizen of the United States, residing in Ardmore, Pennsylvania, have invented certain improvements in Securing Rabble-Arms of Roasting-Furnaces, of which the following is a specification.

The object of my invention is to provide a substantial and close-fitting connection between the central rotating shaft and the projecting rabble arms of an ore-roasting or like furnace, an object which I attain in the manner hereinafter set forth, reference being had to the accompanying drawings, 15 in which—

Figure 1 is a vertical longitudinal section of part of the rotating shaft and part of one of the rabble arms of the furnace, with a connection constructed in accordance with 20 my invention; Fig. 2 is a transverse section of the same, partly in elevation, and Figs. 3, 4, 5, 6 and 7 are views illustrating various modifications of my invention.

Referring, in the first instance, to Figs. 1 25 and 2 of the drawing, 1 represents part of the central, hollow, rotating shaft of the furnace, 2 part of the refractory casing with which the outside of the said shaft is usually provided, in order to protect it from the 30 heat of the furnace, and 3 part of one of the rabble-carrying arms projecting from the shaft into one of the treating chambers of the furnace.

The rabble-carrying arm has, at its inner 35 end, a head 4 of cylindrical or other suitable cross sectional form, which is provided with a beveled shoulder 5, adapted to a seat at the inner end of a hub 6, the latter having a projecting flange 7, or other suitable 40 means, whereby it can be firmly bolted or otherwise secured to the shaft 1, a portion of the hub projecting from this flanged portion into the hollow shaft, as shown at 9. On this inwardly projecting portion of the 45 hub is a boss 10 supported upon wings 11, and perforated for the passage of the threaded stem 12 of a key 13 which passes through slots in the hub 6 and through a slot in the head 4 of the rabble arm, the outer 50 face of the key bearing against the outer walls of the slots in the hub and the beveled inner face of the key bearing against a correspondingly beveled inner wall of the slot in the head 4, as shown in Fig. 1. To the 55 threaded stem 12 of the key are adapted a

pair of nuts 14, the lower nut bearing upon the boss 10 and the upper nut serving as a lock nut. By this means the key 13 can be drawn upwardly and securely locked in position, so as to draw the head 4 of the rabble arm inwardly through the hub 6 and thereby cause the shoulder 5 of said head to bear firmly against the seat at the outer end of the hub, proper readjustment of the key serving to maintain a tight fit between 60 said shoulder and its seat whenever said fit becomes loosened from any cause. A firm and rigid support of the rabble arm upon the shaft is thus provided, which may be maintained in a gas-tight condition so as 65 to prevent leakage of gas from the working chamber of the furnace into the hollow shaft, such leakage being further prevented, if desired, by means of an asbestos or other suitable packing 15 adapted to an external 70 groove in the head 4, as shown in Fig. 1.

Many different means may be employed, within the scope of my invention, for maintaining the tight fit between the rabble arm and the hub, thus in Fig. 3 I have illustrated 80 a pair of gib or keys 16, having their beveled faces in contact and their flat faces bearing, respectively, against the hub 9 and head 4, said keys being recessed for the passage of a bolt 17 having, at the bottom, a head 85 for bearing against one of the keys and at the top a nut 18 adapted to the threaded stem of the bolt and bearing against the other key, while in Fig. 4, I have shown a cam or eccentric 19 carried by a transverse 90 shaft 20 mounted so as to rotate in bearings in the opposite sides of the hub and adapted to elongated slots 40 in the opposite sides of the head 4, said eccentric being contained within a slot 21 in the head 4, and bearing 95 upon the inner wall of the slot and the shaft 20 having, at one end, a lever arm 22 whereby it can be manipulated. The arm 22 is provided with a pawl 23 which engages a toothed segment 24 on the hub, so as to retain the arm 22 in its different positions of adjustment.

In the construction shown in Fig. 5, the head 4 of the rabble arm is provided with threaded blocks 25 having heads 26 let into 105 notches in said head 4, these blocks sliding in keyways 27 in the hub so as to prevent turning of the head 4 in the hub and being engaged by a nut 29 which bears against the inner end of said hub and is provided with 110

suitable arms 30, whereby it can be conveniently turned. The blocks 25, being separate from the cast iron rabble arm head, can have accurate threads cut upon them for engagement with the tightening nut 29, and very fine adjustments of the rabble arm can thereby be effected.

In the construction shown in Fig. 6, a lever 31 is pivotally mounted upon a suitable bracket on the hub 9, one arm of this lever bearing against the inner wall of the slot 21 in the head 4 and its other arm having an internally threaded opening for the reception of an adjusting screw 32 which bears upon the hub 9, and has a suitable lock nut 33 whereby it may be secured into position after adjustment.

In the construction shown in Fig. 7, the head 4 of the rabble arm is toothed, as at 34, for engagement with a pawl 35, hung to the hub 9 and contained in a slot in said hub so as to engage the toothed portion of the head 4 of the rabble arm and retain the same in its adjusted position.

Other modifications will readily suggest themselves to those skilled in the art.

I claim:

1. The combination of a hollow shaft, a hub carried thereby, a rabble arm seated in said hub, and adjustable tightening devices for said rabble arm having an outer bearing on the hub and an inner bearing on the arm and serving to draw said arm directly inward against its seat in the hub without rotating the arm.

2. The combination of a hollow shaft with a rabble arm carried thereby and devices located on the inside of the shaft and serving to secure the rabble arm thereto, said devices being adjustable so as to impart inward movement to the rabble arm.

3. The combination of a hollow shaft, a hub thereon, a rabble arm seated on said hub, threaded blocks secured to the rabble arm, and a nut bearing on the hub and threaded for engagement with the blocks so as to draw the rabble arm inwardly in respect to the hub.

4. The combination of a hollow shaft, an internally recessed hub thereon, an externally recessed rabble arm having a seat on said hub, keys adapted to the recesses in the rabble arm and hub and serving to prevent rotation of the arm in the hub, and means for drawing the arm inwardly in respect to the hub.

5. The combination of a hollow shaft, a hub thereon, a rabble arm having a shoulder seated on said hub, and a head projecting inwardly beyond said shoulder, and means interposed between said inwardly projecting portion of the head and the hub, and serving to draw the shouldered portion of the rabble arm inwardly against its seat on the hub.

6. The combination of a hollow shaft, a hub thereon, a rabble arm having a shoulder adapted to a seat on said hub, and a head projecting inwardly beyond the shoulder, said head having a packing ring for maintaining a tight joint between the same and the hub, and means for maintaining the shoulder on the rabble arm in contact with its seat.

In testimony whereof, I have signed my name to this specification, in the presence of two subscribing witnesses.

UTLEY WEDGE.
